US00D915461S

(12) **United States Design Patent** (10) **Patent No.:** **US D915,461 S**
(45) **Date of Patent:** **** Apr. 6, 2021**

(54) **DISPLAY SCREEN OR PORTION THEREOF WITH ICON**

(71) Applicant: **STAR CO Scientific Technologies Advanced Research Co, LLC, Longview, TX (US)**

(72) Inventor: **Thomas E. Coverstone, Longview, TX (US)**

(73) Assignee: **STAR CO SCIENTIFIC TECHNOLOGIES ADVANCED RESEARCH CO, LLC, Longview, TX (US)**

(**) Term: **15 Years**

(21) Appl. No.: **29/703,459**

(22) Filed: **Aug. 27, 2019**

(51) LOC (13) Cl. **14-04**

(52) U.S. Cl.

USPC **D14/489**

(58) **Field of Classification Search**

USPC **D14/485-495; D20/11**

CPC **G06F 3/048-04897**

See application file for complete search history.

(57) **CLAIM**

The ornamental design for a display screen or portion thereof with icon, as shown and described.

DESCRIPTION

The patent file contains at least one drawing executed in color. Copies of this patent with color drawings will be provided by the Office upon request and payment of the necessary fee.

FIG. 1 is a front view of a display screen or portion thereof with icon showing my new design according to a first embodiment; and,

FIG. 2 is a front view of a display screen or portion thereof with icon showing my new design according to a second embodiment.

The broken lines in the figures depict a display screen or portion thereof and form no part of the claimed design.

**1 Claim, 2 Drawing Sheets
